UNITED STATES PATENT OFFICE.

THOMAS CHESTER LLOYD, OF PORTSMOUTH, OHIO, ASSIGNOR TO THE IRVING DREW COMPANY, OF PORTSMOUTH, OHIO, A CORPORATION OF OHIO.

DESIGN FOR A SOLE FOR BOOTS, SHOES, OR SIMILAR ARTICLES.

59,849.

Specification for Design.

Patented Nov. 29, 1921.

Application filed October 18, 1920. Serial No. 417,843. Term of patent 14 years.

To all whom it may concern:

Be it known that I, THOMAS CHESTER LLOYD, a citizen of the United States, residing at Portsmouth, in the county of Scioto and State of Ohio, have invented a new, original, and ornamental Design for a Shoe-Sole, of which the following is a specification, reference being had to the accompanying drawings, forming a part thereof.

Figure 1 is a bottom plan view of a shoe sole embodying the design.

Fig. 2 is a side elevation of the shoe sole, looking at the outer edge of the sole, the upper and heel being shown in dotted lines, representative of any shape and configuration of shoe.

Fig. 3 is a section through the sole on line 3, 3, Fig. 2.

The design, as shown, comprises a sole in which the shank portion presents three sur-

faces, a central, longitudinal surface in approximately a horizontal plane corresponding to and merging with the palm surface of the sole and of the same shade or color thereof, and two opposite, transversely, angular surfaces 2, 3, respectively at relative opposite sides of the central surface, and of a distinguishing shade or color than the central surface.

The novel feature of the design of sole as shown is independent of the shoe upper.

I claim:

The ornamental design for a sole for boots, shoes or similar articles, as shown and described.

THOMAS CHESTER LLOYD.
